UNITED STATES PATENT OFFICE.

EDWIN J. HOWE, OF NEWARK, NEW JERSEY, ASSIGNOR OF ONE-HALF TO
GEORGE R. HOWE, OF SAME PLACE.

DESIGN FOR A COMMUNION-SERVICE TRAY.

SPECIFICATION forming part of Design No. 23,901, dated December 25, 1894.

Application filed November 17, 1894. Serial No. 529,188. Term of patent 14 years.

To all whom it may concern:

Be it known that I, EDWIN J. HOWE, a citizen of the United States, residing at Newark, in the county of Essex and State of New Jersey, have invented and produced a new and original Design for Communion-Service Trays; and I do hereby declare the following to be a full, clear, and exact description of the same, reference being had to the accompanying drawings, forming a part thereof.

This invention relates to a new and original design for communion service trays, and it consists generally in the peculiar shape and arrangement of the same.

In the accompanying drawings wherein a tray fashioned after my design is shown—Figure 1 represents a perspective view of the tray; Fig. 2, an elevation thereof.

In the drawings A designates the bottom tray, of ring-shape having a flat upper face and on which is a circular series of closely arranged holding devices for the individual glasses. From the inner edge of the ring A extend the supports B on which is the upper

tray C, which upper tray has a closely arranged circular series of glass holders near its edge.

The tray C has a closed central portion, from the center of which projects the handle D which is in the form of a cross.

The ring A has suitable supports on its under side.

The essential feature of the design is the lower tray A and the upper tray C supported above the same with a handle at the center extending up above the tray.

Having thus described the invention, what is claimed as new, and desired to be secured by Letters Patent, is—

The design for a communion service tray, substantially as shown and described.

In testimony whereof I affix my signature in presence of two witnesses.

EDWIN J. HOWE.
